SPINNING TOY

Filed Sept. 26, 1945

UNITED STATES PATENT OFFICE

2,397,674

SPINNING TOY

Harry A. Loomis, Los Angeles, Calif.

Application September 26, 1945, Serial No. 618,627

10 Claims. (Cl. 46—63)

My invention relates to a spinning toy, and has for its principal object the provision of a relatively simple, practical and inexpensive toy or plaything that will afford interest and amusement to the user, and the manufacturing cost of the toy being such as to enable it to be economically used as an advertising medium.

A further object of my invention is to provide a spinning toy that consists of a body member which may be formed of thin light-weight material such as cardboard, Celluloid or thin metal, and said body member being mounted upon a doubled string so that said body member may be caused to rotate rapidly, first in one direction and then in the other, as the doubled portions of the string to the sides of the body member are twisted and untwisted as a result of proper manipulation of the hands of the operator.

A further object of my invention is to provide a spinning toy having an integral projecting flap or flaps on the opposite sides of which are printed parts of letters, figures, pictures or characters which, as the toy is spun, blend to form words, pictures and the like and thereby add materially to the attractiveness and value of the toy, particularly when used for advertising purposes.

With the foregoing and other objects in view, my invention consists in certain novel features of construction and arrangement of parts which will be hereinafter more fully described and claimed and illustrated in the accompanying drawing in which:

Fig. 1 is a perspective view of one form of the spinning toy.

Fig. 2 is a vertical section taken lengthwise through the center of the form of toy seen in Fig. 1.

Fig. 3 is a horizontal section taken on the line 3—3 of Fig. 1.

Fig. 4 is a section similar to Fig. 3 and showing the reverse side of one of the parts of the toy.

Fig. 5 is a perspective view of a merchandise carton with the outlines of the main parts of the toy printed on one of the walls thereof.

Fig. 6 is a perspective view of a modified form of the toy.

Figure 7 is a horizontal section taken on the line 7—7 of Fig. 6.

Fig. 8 is a vertical section taken on the line 8—8 of Fig. 6.

Fig. 9 is a plan view of a further modified form of the toy.

Fig. 10 is a cross section taken on the line 10—10 of Fig. 9, with the two parts of the toy body disposed at right angles to each other.

Fig. 11 is a plan view of a further modified form of the toy.

Fig. 12 is a section taken through the center of the form of toy shown in Fig. 11 with the parts of the toy body disposed at right angles to the other.

Referring by numerals to the accompanying drawing, particularly Figs. 1 to 5 inclusive, 10 designates the main body of the toy, which may be formed from thin sheet material, such as card board, plastics or the like, of any desired shape and the side faces may be plain or colored or may bear printed and illustrated advertising matter.

Formed through the center of body 10 is a short slot 11 and formed near one or both ends of the body, is an aperture such as 12, which when the body spins at considerable speed, produces a whistling sound.

A narrow strip of thin material is folded at 20 the center to produce a double thickness arm 13, provided on its sides near the line of fold with shoulders 14 and said arm tapering gradually in width away from said shoulders. Thus when arm 13 is inserted in and moved through slot 11, the side edge of said arm adjacent the shoulders 14 wedge against the ends of said slot and thereby maintain the body 10 and arm 13 in assembled relation.

Formed through arm 13 adjacent the shoulders 30 14, is an aperture 15 and passing therethrough and through slot 11 is the end of a doubled string or thread 16.

Formed in the opposite end of arm 13 is an aperture 17 and passing therethrough is the inner 35 end of a double string or thread 18. The outer faces of arm 13 bear mutilated or parts of letters such as 19 and said parts being disposed with relation to each other, so that when the toy is spinning at high speed, the parts of the letters merge and form a word or words.

The toy is spun by first twisting strings 16 and 18 and then exerting pull thereon to cause same to untwist and as these actions are repeated, the body of the toy will rotate at high speed first in 45 one direction and then in the other.

In Fig. 5, I have shown the parts of the toy printed in outline on one of the walls of a paper or cardboard carton used in merchandising various products and thus when the contents of the 50 carton have been removed, the parts forming the body of the toy may be cut from the carton, which procedure tends to add materially to the advertising and sales value of the product contained in the carton.

55 In the modified construction illustrated in Figs.

6, 7 and 8, 20 designates the body of the toy, preferably formed of cardboard of any desired size and shape and secured to the center thereof is a tab 21, bent at right angles from the end of an arm 22 and formed through said tab just above its line of connection with arm and through body 20 are connecting apertures 23.

A staple 21a preferably of fine wire is used for securing tab 21 to body 20 and said staple passes across the apertures 23, thus forming in effect, two apertures through which pass the strands of the twisted cord or thread 24, used in spinning the toy. One end of the cord 24 passes through an aperture 25 formed in the outer end of arm 22.

In this form of toy, both sides of body 20 may be colored, decorated or printed as desired and the opposite faces of arm 22 may bear parts of letters which, when the toy is spun, blend into a word or words.

In Figs. 9 and 10 I have shown the toy body 26 shaped to represent or simulate the wings of a butterfly with an integral medial portion 27 representing the body and the letter being bent at the dotted line X so as to project outwardly at right angles from the wings (see Fig. 10).

Formed through the outer end of member 27 is an aperture 28 and a pair of apertures 29 are formed in said member on opposite sides of dotted line X. A twisted double cord or thread 30 for spinning the toy passes through aperture 28 and the strands of said cord pass through the apertures 29.

In Figs. 11 and 12 a body 31, of any desired size and shape, has formed integral therewith a narrow strip 32, the inner portion of which is extended to the center of said body by slitting the latter inwardly from its edge as designated by 33. Strip 32 is bent double at the transverse dotted line 34 and the inner end of said strip is bent at right angles to body 31 at the dotted line 35.

Formed in the ends of strip 32 are apertures 36 which coincide with each other when said strip is folded double and similar apertures 37 are formed in said strip in opposite sides of dotted line 34 and which coincide with each other when the strip is doubled.

An aperture 38 is formed through body 31 on the opposite side of dotted line 35 from aperture 36 and to produce a whistling sound when the toy is spun, a larger aperture 39, is formed in body 31 near its outer edge.

The twisted doubled cord or thread 40 used in spinning the toy passes through the coinciding apertures 37, with one strand of said cord passing through the coinciding apertures 36 and aperture 38 (see Fig. 12).

Thus it will be seen that my improved toy provides an amusing, interesting and attractive plaything for children and its inexpensive construction enables it to be advantageously employed as an advertising medium.

It will be understood that minor changes in

the size, form and construction of the various parts of my improved toy may be made and substituted for those herein shown and described without departing from the spirit of the invention, the scope of which is set forth in the appended claims.

I claim as my invention:

1. A toy comprising a body member of thin sheet material, a narrow strip of thin material secured to and projecting at right angles from the central portion of said body member, and a doubled cord connected to the center of said body and to said narrow strip.

2. A toy as set forth in claim 1 and the side faces of which strip bears mutilated letters which, when the toy spins, merge into a word or words.

3. A toy as set forth in claim 1 with said body and strip provided with apertures for the accommodation of said doubled cord.

4. In a spinning toy, a body of thin sheet material provided near its center with an aperture, a narrow strip of thin material passing through said aperture, which strip is provided near its ends with apertures and a doubled cord, passing through the apertures in said body and strip.

5. A spinning toy as set forth in claim 3 with shoulders formed on the sides of said strip near one end for engagement against said body.

6. A spinning toy as set forth in claim 4, with the side faces of which strip bearing mutilated letters which when the toy is spun, merge and form a word or words.

7. In a spinning toy, a body of thin sheet material, a narrow strip of thin material having one end bent at right angles and bearing on the center of said body, there being coinciding apertures found in said bent end and body, there being an aperture formed in the outer end of said strip and a doubled cord passing through said apertures.

8. A toy as set forth in claim 7, with a staple fastening the bent end of said strip to said body, which staple passes across said coinciding apertures so as to separate the strands of said cord at the point where they pass through said coinciding apertures.

9. A spinning toy comprising a body of thin sheet material, a narrow strip of material having one end integrally connected to the center of said body, there being apertures formed in said body and strip adjacent the point where the same are joined, there being an aperture formed in the outer end portion of said strip and a doubled cord passing through said apertures.

10. In a toy, the combination with a body of thin sheet material, of a narrow strip of thin material secured to and projecting at right angles from the center of said body on one side thereof, and a doubled operating cord associated with said body and strip.

HARRY A. LOOMIS.
